(57) **CLAIM**

The ornamental design for a methane monitoring system as shown and described.

DESCRIPTION

FIG. 1 is a perspective view of a methane monitoring system from below.

FIG. 2 is another perspective view of the methane monitoring system from below. The perspective view of FIG. 2 is rotated approximately 90 degrees from the perspective view of FIG. 1.

FIG. 3 is another perspective view of the methane monitoring system from above.

FIG. 4 is a side view of the methane monitoring system.

FIG. 5 is another side view of the methane monitoring system. The side view of FIG. 5 is rotated approximately 90 degrees from the side view of FIG. 4.

FIG. 6 is another side view of the methane monitoring system. The side view of FIG. 6 is rotated approximately 180 degrees from the side view of FIG. 4.

FIG. 7 is a top view of the methane monitoring system; and, FIG. 8 is a bottom view of the methane monitoring system. The broken lines in the drawings depict unclaimed environmental subject matter.
